CHECK BOOK CLIP

Stuart T. Shears, Belmont, Mass., assignor to United Carr Fastener Corporation, Cambridge, Mass., a corporation of Delaware

Filed Sept. 25, 1958, Ser. No. 763,232

1 Claim. (Cl. 24—259)

This invention relates generally to the art of fastening a group of thin rectangular pieces together and more specifically to fastening a group of checks together.

It is an object of the present invention to provide a checkbook clip which has flat surfaces bearing on top and bottom of the group of checks.

Another object of the invention is to provide a checkbook clip wherein the tearing portion conforms to the perforations on the checks.

A further object of the invention is to provide a checkbook clip having a ribbed base for strength and to cooperate with the tearing portion in holding the checks.

A still further object of the invention is to provide a checkbook clip having cutouts in the base for greater range in accommodating a number of checks.

In the drawing:

FIG. 1 is a top plan view of a preferred embodiment of the applicant's clip;

FIG. 2 is a bottom plan view of the clip shown in FIG. 1;

FIG. 3 is a cross sectional view of the clip taken on line 3—3 of FIG. 2; and

FIG. 4 is a cross sectional view of the clip applied to a group of checks and attached to a cover, the cover being broken off.

Referring to the drawings, there is illustrated a preferred embodiment of the applicant's improved checkbook clip comprising a base or leg portion 10, a connecting portion 12, and upper leg portion 14 in spaced angular relationship with said base portion 10. Both the base 10 and leg 14 are integral with said connecting portion 12 to form a substantially arched shaped clip. Said connecting portion 12 is in substantially right angular relationship with the base 10. The leg portion 14 is rectangular in form and comprises a leading edge 16 and two side edges 18. The leading edge 16 is bent from the angular relationship with base 10 to a substantially parallel spaced relationship with the base 10 as best illustrated in FIG. 3, forming a contact portion 11. The side edges 18 of the leg 14 are bent slightly away from the direction of the base 10 to form leads for engaging the checkbook 20. The base 10 is rectangular in form and its formed edge 22 extends beyond the leading edge 16 of the leg 14 as best shown in FIG. 3. The base 10 has two sides 24, a trailing edge 26 and the formed edge 22. An embossed rib 28 is formed on the margin of the base 10 running along the forward edge 22, the sides 24 and a portion of the trailing edge 26 of the base 10 as shown in FIG. 1. The rib 28 protrudes toward the plane of the leg 14 and extends to the points where the connecting portion 12 is integral with base 10 as illustrated in FIG. 1. The sides 24 of the base 10 extend beyond the side edges 18 of the leg 14. To engage a group of checks 20 with applicant's clip, the checks are passed over a side 24 of the base 10 and under a side 18 of the leg 14. The length of

2

the leading edge 16 is normally made equal to the width of the checks 20 although this is not absolutely necessary. The checks 20 will now be held securely by the pressures which are exerted at approximately right angles to the checks 20. These pressures are exerted first by the embossed rib 28, secondly by the leading edge 16 in an opposite direction and thirdly, by that portion of the embossed rib 28 which lies parallel to the trailing edge 26 of the base 10. The leading edge 16 of the leg 14 contacts the check 20 not on a thin line but on a substantially broad surface.

In order to increase the number of checks which the clip will hold, apertures 32 may be formed on the margin where the trailing edge 26 of the base 10 contacts the connecting portion 12. Theoretically, the larger the area of the aperture 32, the greater the number of checks the clip will hold efficiently. The form of the apertures 32 may be of any geometric types, the applicant has used the type shown in FIG. 2 of the drawing effectively. There are many different methods of attaching the clip to a checkbook cover 34. Applicant has used in the preferred embodiment here shown, a rivet 36 through two apertures 38 formed in the base 10 in the areas not covered by the leg 14. The size of the apertures 38 can be increased to accommodate a heat sealing fastener if required.

While I have illustrated and described a preferred embodiment of my invention, reference is made to the following claim which best defines the scope of my invention.

I claim:

A clip for check books and the like formed from a single piece of metal having a base portion, and an upper superposed spring leg having side edges and a connecting portion securing said base and leg together along adjacent edges, said base having a continuous rib extending toward the plane of said leg along a first edge opposite the connecting portion and along said side edges, and said rib having ends directed inwardly toward each other along an edge of said base opposite said first edge to support a book of checks and the like in spaced relation to said base portion, and said spring leg being of less width than the distance between the ribs along said side edges of said base, and being normally angled toward the base from the connecting portion, and having a leading edge normally spaced therefrom and terminating near the rib on said base at said first edge opposite the connecting portion, and a contact portion adjacent the said leading edge of said leg and located close to said rib and adapted to press said book of checks toward said base portion adjacent the said rib to form a bend in the check book and help hold said check book in place, one of said side edges being bent away from said base portion.
